PILOT CONTROL MEANS

Alfred Wild, Milwaukee, Wis.

Application December 12, 1930, Serial No. 501,836

2 Claims. (Cl. 158—115)

This invention relates to improvements in pilot control means.

One of the objects of the present invention is the provision of a pilot light adapted to be used 5 in connection with a plurality of burners, wherein the ignition lights from the pilot are discharged directly toward the burners in such manner that when the fuel is turned onto the burners, the pilot light will quickly ignite the same, and means is 10 provided whereby to automatically increase the light of the pilot so that it will reach the burner when the fuel is turned into the burner.

Another object of the present invention is the provision of an improved pilot light attachment 15 for stove burners, wherein the operating mechanism for the pilot light is operatively connected with each individual control for the burners, so that when any one of the burners is turned on for admission of fuel to the burner, the control 20 for the pilot light will be automatically actuated for increasing the amount of fuel being fed to the pilot so that the flame of the pilot will readily reach the burner and ignite the same, and wherein continued movement of the individual control 25 for the burner turned on will decrease the extra force for the pilot, so that it will resume its normal burning position.

A further object of the invention is the provision 30 of an improved device of the above character, wherein a separate flash-head is provided for the oven burner, and means is provided for automatically igniting this flash-head when the control for the oven burner is actuated to admit fuel thereto, so that the flash-head for the oven will 35 be ignited and in turn ignite the oven burner.

With the above and other objects in view, the invention consists in the novel features of construction, the combination and arrangement of parts hereinafter more fully set forth, pointed 40 out in the claims and shown in the accompanying drawings wherein:

Figure 1 is a top plan view of a gas stove, illustrating the application of my improved device;

Figure 2 is a sectional view on a line 2—2 of 45 Figure 1;

Figure 3 is a detailed section on the line 3—3 of Figure 2;

Figure 4 is a detailed section on the line 4—4 of Figure 2;

Figure 5 is a detailed transverse section on the 50 line 5—5 of Figure 1;

Figure 6 is a plan view of a slightly modified form of control for the pilots; and,

Figure 7 is a longitudinal sectional view through 55 the control device shown in Figure 6.

Referring more particularly to the drawings, I indicates the main portion of the stove having an oven 2 at one side thereof. Above the body portion 1 of the stove, I provide a plurality of burners 3, each burner having connected therewith a conduit 4 provided with the usual air mixer 5 and connected up with the main conduit 6 by means of the lateral branch portion 7 in which are arranged the control valves 8 adapted to be actuated by the hand wheels 9.

Each of the branch pipes 7 have attached thereto, a bracket 10 provided with an upstanding portion 11 which carries a headed guide pin 12. These guide pins 12 operate in slots 13 formed at spaced intervals in the reciprocating bar 14.

The valve stem of each valve has mounted thereon, a cam member 15, which is adapted to engage one end of an inclined finger 16. It will be noted that the end of each finger adjacent its respective cam 15 is enlarged laterally to form 20 an engaging surface, and due to the fact that the fingers are disposed in an inclined position relative to the bar 14, the bar 14 will be reciprocated on the guide pins 12 when any of the several valves 8 are actuated.

The fingers 16 are secured to the bar 14 by 25 means of screw members 17 and are supported in an inclined position by means of the stop pins 18. Arranged within the oven 2 is the oven burner 19 connected up to the main supply conduit 6 by means of a conduit 4', having a branch 1' in which is arranged the valve 8', the branch 1' being connected with the main supply conduit 6.

The slot 13' in bar 14 receives the guide pin 35 12' carried by a bracket attached to the branch pipe 1' and attached to the bar 14 adjacent the slot 13' is a finger 16' adapted to be engaged by the cam 15'. This finger 16' is provided with a somewhat larger end portion than 40 the fingers 16, due to the fact that when cam 15' is actuated upon admitting fuel into the oven burner, it is required that the bar 14 be reciprocated a greater distance than when fuel is admitted to the burners 3. The cam 15' is 45 also provided with a longer engaging nose as will be clearly noted in Figure 2.

Arranged between the conduit 4 for two of the burners 3 are the conduits 20 and 21. The conduit 20 has at its outer end a pilot housing 22, 50 provided with radially positioned openings in the side walls thereof which are preferably on a line with the different burners 3, with the exception of one opening which is positioned in alignment with the inner open end of an elong- 55

gated housing 23. From the showing in Figure 1, it will be noted that the pilot housing 22 has its openings opening toward the burners 3 and the housing 23. The conduit 20 is connected up 5 with a nipple 24 on housing 25. Threaded into each end of housing 25 are the removable housings 26 and 26'. The valve housing 26 communicates with the nipple 24 and is provided with a valve seat 27 on which is normally seated a 10 valve 28.

The valve housing 26 communicates with a chamber 29 in housing 25, and this chamber is connected up with the main supply conduit by means of a nipple 30. Leading from the chamber 29 into the nipple 24 is a small angular passage 31, in one end of which is arranged a needle valve 32, controlling passage of the fluid from chamber 29 through the angular passage 31. Ordinarily, this valve 32 is opened so that a small 15 amount of gas or other fluid is admitted to the pilot 22 to keep the same burning sufficiently to readily ignite the burners 3 when the case requires.

The valve 28 is provided with a valve stem 25 33 having attached to its outer end a plunger 34 which carries a threaded stud 35 and adjustably mounted on this stud is a stop plate 36 integral with the lateral projection 37 on the lower edge of the bar 14. The valve housing 26 30 is provided with a partition 38 through which the valve stem 33 moves and positioned between the plunger 34 and the partition 38 is a coil spring 39 which surrounds the valve stem 33 to normally 35 maintain the valve 28 in a seated position.

The conduit 21 heretofore referred to leads to an apertured flash-head 40 arranged in the elongated housing 23 at a point adjacent the oven, and this conduit 21 is detachably connected to the nipple 41 which has direct communication 40 with the valve chamber 26'. The valve chamber 26' is formed with a valve seat 42 on which is normally seated a valve 43. The stem 44 of valve 43 is slidably mounted in a bore 45 in the removable plug 46 arranged in one end of the 45 valve housing 26'. Positioned on the valve stem 44 and arranged between the plug 46 and the valve 43 is a coil spring 47 which normally maintains the valve 43 in a closed position.

At this point, I wish to call attention to the 50 fact that the valve 28 is provided with an auxiliary stem 48 which extends into the chamber 29 and valve 43 is provided with an auxiliary stem 49 which extends into chamber 29 in longitudinal alignment with the extension or auxiliary stem 48.

The valve 28 is normally urged to a seated position by means of the comparatively heavy spring 50, arranged in the chamber 29 and around the two auxiliary stem portions 48 and 49. One end 60 of this spring 50 bears against a washer 51 which is fitted against the valve 28, while the other end of the spring bears against a similar washer mounted on the auxiliary stem 49 and bears against the inner end of valve housing 26', as 65 clearly illustrated in Figure 4.

Connected to the branch portion 1' of the conduit 4' is a small conduit 52 which leads into the elongated housing 23 adjacent the head member 40 and then continues out through the 70 end of housing 23 which opens into the oven 2 and an igniting pilot 53 is attached to the end of the conduit 52 adjacent the oven burner 19 for igniting the oven burner when fuel is admitted to this burner.

It will be noted from the showing in Figure 1, that when the pilot 22 is turned on with a comparatively heavy force, the flame which passes into the housing or chamber 23 will ignite gas flowing from the flash-head 40, the head 40 being provided with oppositely positioned openings, one facing the pilot 22 and the other facing the pilot 53, the flash-head 40 being ignited from pilot 22 and in turn igniting the oven burner 19.

From the above description, it will be readily noted that normally the pilot 22 is continually burning with a very small flame, due to the admittance of fuel passed the needle valve 32. However, when one of the valves 8 is actuated for admitting fuel to one of the burners 3, the 10 rotation of the valve stem will actuate the cam 15 carried thereby which in turn will engage the end of its respective finger 16 and reciprocate bar 14. The reciprocation of bar 14 will impart movement to the plunger 34 for unseating valve 20 28, this movement will admit the fluid under pressure to the pilot 22 and as the openings in the pilot light are such as to project the flame for a considerable distance, the burner 25 into which fuel has been admitted will be ignited by one of these projecting flames. Attention is directed to the fact, however, that as the valve continues in its opening movement, the cam 15 will pass finger 16, therefore releasing bar 14 whereby the tension of the springs 39 and 30 50 will not only return the valve 28 to its seat 27, but will return the bar 14 to its normal position, illustrated in Figure 2, and also cut the supply of fuel to the pilot 22 down to normal or the amount which flows past the needle valve 32. 35

In operating the oven burner, attention is directed to the fact that when the valve 8 is actuated for admitting fuel to the burner 19, the bar 14 is reciprocated a longer distance than in the reciprocation due to the opening of one of 40 the valves 8. This movement of bar 14, through the engagement of cam 15' with finger 16' will cause the auxiliary stem portion 48 to valve 27 to contact with the auxiliary stem portion 49 to valve 43, unseating valve 43 and permitting the 45 fuel to flow in through nipple 41 and conduit 21 to flash-head 40.

Attention is directed to the fact that when valve 8' is opened, the fuel is admitted to the conduit 52 and to the oven burner therefore, when 50 the valve 43 is unseated and fuel admitted to the flash-head 40, the head 40 will be ignited from the projected flame of pilot 22 and in turn will ignite the oven burner and the safety pilot 53.

The operation, through the movement of valve 55 8', is similar to the other valves, as cam 15' will pass the end of finger 16' after a predetermined opening movement of valve 8, so that the spring members 39, 47 and 50 will return valves 28 and 43 to their normally seated positions. In view of 60 the fact that all of the fingers, including finger 16' are pivotally mounted, the valves 8 and 8' can be readily moved to a closed position without imparting any movement to bar 14.

Referring more particularly to Figures 6 and 7, 65 wherein I have illustrated the modified control for the main pilot and the oven pilot, it will be noted that the conduit 55 which leads into a main housing 56 communicates with a central chamber 57. Threaded into each end of the housing 56 70 are the valve housings 58 and 58'. The valve housing 58' is provided with a chamber 59 which communicates through passage 60, with the main supply pipe 61.

Communication is established between cham- 75

bers 57 and 59 by means of a short passage 62 having a valve seat at the end leading into chamber 57 upon which is normally seated a valve 63. The valve 63 is provided with a main stem 64 mounted for reciprocating movement in the partition walls 65.

Slidably mounted in the valve housing 58 is a plunger 66 having a head 67 adapted to be manually compressed for urging the valve 63 from its seat. A coil spring 68 normally maintains the valve 63 in a seated position.

The plunger 6 is provided with an annular groove 69 adapted to receive a spring-pressed ball 70 when plunger 66 is pressed inwardly to indicate the relative position of the valve 63 when opening passage from the main conduit 61 to the chamber 57.

A bleed conduit 70 is provided between chambers 57 and 59 and passage therethrough is controlled by the needle valve 71 whereby the main pilot may be provided with a continual supply of fuel. The inner end of the valve stem 64 projects beyond the valve 63 for a short distance, as shown at 72.

The outer end of the valve housing 58' is normally closed by means of a plug 73 having a central bore 74 in which the inner end of valve stem 75 is slidably mounted. The valve stem 75 carries a valve 76 which normally closes communication between the valve housing 58' and chamber 57. The valve 76 is normally maintained in a seated position by means of the coil spring 77.

The valve stem 75 projects beyond the valve 76 to form an auxiliary stem portion 78, positioned in alignment with the extended portion 72.

It will be apparent that in the use of this manually controlled type of device, the valve 63 will be unseated by pressing inwardly upon the head 67.

As the groove 69 reaches the ball 70, it will indicate to the operator that the valve 63 is opened sufficiently to provide the proper amount of increase of fuel to the main pilot for igniting any one of the burners in close proximity to the pilot. However, when it is desired to provide a supply of fuel to the conduit 79 which leads to the oven burner, the plunger 66 is forced inwardly until the extended part 72 of valve stem 64 engages the extension 78 to valve stem 75 which will unseat the valve 76 and permit the passage of

fluid through the conduit 79 to the flash-head for the oven burner.

This manually actuated type of control for the pilots, may be used in place of the automatically operated control illustrated in Figure 4, and described as the preferred construction.

The device is very simple and can be manufactured and applied to gas stoves where more than one pilot light is desired for igniting the various burners.

It will be apparent from the foregoing that I have provided a comparatively simple and inexpensive device, wherein any one of the several burners of the stove can be quickly ignited from a centrally located pilot and the oven burner can also be ignited from the same pilot by providing the intermediate head 40.

I claim:

1. A valve for use in connection with a lighter for the burner of a gas cooking stove comprising a housing having spaced fuel outlets at one side for connection respectively with a pilot and a flashhead and a fuel inlet at another side, opposed spring actuated valves normally fitted in said housing to close communication between the inlet and said outlets, means whereby to open one of said valves a predetermined distance to provide communication with the inlet and one of the outlets, and means whereby to open the other of said valves from the first valve, after the first valve has been open a predetermined distance to establish communication between the inlet and the other of said outlets.

2. In combination with a gas range an oven burner and a constant burning pilot light remote therefrom, a pilot light adjacent the oven burner, a pilot light intermediate the oven pilot light and the constant burning pilot light, means to simultaneously deliver gas to the oven burner and said oven and intermediate pilot lights, a flash tube between the constant burning pilot light and the intermediate pilot light, a flash tube between the intermediate pilot light and the oven pilot light, said constant burning pilot light igniting the intermediate pilot light by a flash and the intermediate pilot light lighting the oven pilot light by a flash through said tubes when gas is delivered to the oven burner and said intermediate and oven burner pilot lights as defined.

ALFRED WILD. 50
